UNITED STATES PATENT OFFICE

ARNOST JANOVSKY, OF BROOKLYN, NEW YORK, ASSIGNOR TO INTERSTATE ELECTRIC NOVELTY COMPANY, OF BROOKLYN, NEW YORK, A CORPORATION OF NEW YORK.

POCKET FLASH-LIGHT.

1,263,674.

Specification of Letters Patent. Patented Apr. 23, 1918.

Application filed August 27, 1917. Serial No. 188,273.

To all whom it may concern:

Be it known that I, ARNST JANOVSKY, a citizen of the United States of America, residing at the borough of Brooklyn, county of Kings, city and State of New York, have invented certain new and useful Improvements in Pocket Flash-Lights, of which the following is a full, clear, and exact description.

10. This invention relates to improvements in pocket flash lights the object being to provide a lamp of such a construction as to present a unique appearance as well as to possess the advantages which will be set forth.

I will now proceed to describe my invention in detail, the novel features of which will be pointed out in the claims, reference being had to the accompanying drawing 20 wherein,

Figure 1 is a side view of the lamp,

Fig. 2 is a vertical central section partly in elevation, and

Fig. 3 a fragmentary detail view of the 25 switch.

My improved lamp consists of a casing 4 reduced at its lower end 5 which is threaded at 6 to receive an elongated cap 7 containing a spring 8 which acts to force the battery 9 longitudinally of the casing to cause the pole 10 to contact with the lamp 11 in the usual manner. The spring 8, as usual contacts with the zinc of the battery 9 the circuit being through the spring, cap 7, casing 4, 30 switch 12, reflector 13, which carries the lamp 11, thence back to the battery. The reflector 13 is kept out of contact with the casing 4 by a bushing 14 of insulating material. As the casing 4 is made somewhat 35 larger than the battery 9, I provide rings 15 and 16 through which the battery is slipped from the bottom of the casing when cap 7 is removed. The rings 15 and 16 prevent the battery from lashing around in the casing. 40 The internal diameter of the cap 7 is but little more than the diameter of the battery 9. Thence it is kept from lashing at its lower end.

The switch 12 consists of a flat strip of 50 metal secured to a button 17 having clips 18

which pass through a slot 19 in the casing 4 and engage the switch 12. The only insulated portion of the battery is the upper end at which point the bushing 14 is located. When the button 17 is pushed toward the 55 lamp the switch 12 will contact with the reflector 13 and the circuit will be complete. By making the casing 4 as above set forth, I am able to do away with insulation to protect the switch as the switch is kept out of 60 contact with the battery by the spacing rings 15 and 16. The switch strip 12 is the only strip employed and I do not employ a strip connecting the spring 8 and switch 12 as is usual in pocket flash lamps. The switch 65 or strip 12 is in direct contact with the metal casing 4.

What I claim is—

1. In a pocket flash lamp, the combination of a casing, a battery carried thereby, 70 said casing being larger in diameter than said battery, spacing rings carried by the casing adapted for the passage therethrough of said battery, said casing being reduced in diameter, at one end thereof, the reduced 75 portion of the casing being arranged to approximately fit the adjacent end of the battery, an elongated cap removably secured to the reduced end of the casing, a spring carried by the cap bearing against the battery, 80 and a slidable switch carried by the casing.

2. In a device as described, in combination, a casing, a battery disposed concentrically therein, the lower portion of said casing being reduced, a cylindrical tapering 85 cap having its larger end removably secured to the reduced portion of said casing, one end of said battery being embraced by the reduced portion of said casing, a lamp secured to the opposite end of said casing, 90 and a spring wedged in said cylindrical tapering cap and engaging the adjacent end of said battery to force its opposite end to electrically engage said lamp.

Signed at New York city, N. Y., this 22 95 day of August, 1917.

ARNOST JANOVSKY.
